UNITED STATES PATENT OFFICE.

HERBERT E. VAN DORN, OF CHICAGO, ILLINOIS.

COMBINED CROSS-CONNECTING SWITCH AND COUPLER FOR ELECTRICAL AND AUXILIARY AIR LINES.

Application filed April 19, 1922. Serial No. 555,644.

My invention has for its object to produce a simple, compact and efficient coupler by means of which electrical connections may be reliably made between two cars, the circuits will be cross connected when two similar cars are coupled together, thus permitting the use of a minimum number of contacts, and by means of which the air system for controlling the pneumatic actuating devices associated with the coupler and, if desired, the car coupler, will be connected to the corresponding system on another car so as to cause the various operations in coupling and uncoupling to take place in unison on both cars when a master valve on either car is operated.

A further object of the present invention is to produce a simple and compact construction and arrangement whereby a movable contact carrier adapted to co-operate with a similar carrier on another car will normally be effectively housed within a suitable casing containing also a simple cross connecting switch, the parts being so constructed and arranged that the door in the casing must be opened before the contact carrier can be moved in a direction tending to project it from the casing.

Another object of the present invention is to produce a simple and novel electric coupler combining a movable contact carrier and a cross connecting switch.

A further object of the present invention is to produce a simple and novel electric coupler having a closure for protecting the parts in the interior thereof when the coupler is not co-operating with another coupler, and having the actuating controlling means for the movable parts so interlocked that they are compelled to move in the proper sequence to avoid interference with each other, although they may be controlled from a single master controller.

The various features of novelty whereby my invention is characterized will hereinafter be pointed out with particularity in the claims; but, for a full understanding of my invention and of its objects and advantages, reference may be had to the following detailed description taken in connection with the accompanying drawings, wherein:

Figure 1 is a top plan view of my improved coupler, including the necessary piping and a master valve shown diagrammatically;

Fig. 2 is a section on an enlarged scale taken approximately on line 2-2 of Fig. 1;

Fig. 3 is a section taken approximately on line 3-3 of Fig. 5;

Fig. 4 is a section taken approximately on line 4-4 of Fig. 5;

Fig. 5 is a horizontal section, on a smaller scale, taken approximately on line 5-5 of Fig. 4;

Fig. 6 is a section taken approximately on line 6-6 of Fig. 4, on a somewhat smaller scale than the latter;

Fig. 7 is a section taken approximately on line 7-7 of Fig. 5, but on a larger scale than the latter; and

Fig. 8 is a section through the front end of the contact carrier taken approximately on line 8-8 of Fig. 7.

Referring to the drawings, 1 represents a suitable casing or housing open at the front end and provided with a door 2 having rearwardly-projecting flanges or wings 3 and 4 pivotally connected to the side walls of the casing by suitable bolts 5, so as to permit the door to swing between a position in which it closes the front of the casing to a position in which it lies underneath the front end of the casing. As best shown in Fig. 3, there is in one side of the casing a longitudinally-slidable spring-pressed plunger 6 lying in rear of and engaging with a nose 7 on one of the wings of the door below the hinge axis. When free to do so, this plunger closes the door, and the door can be opened only by pressing back the plunger.

On the same side of the casing as the plunger 6, above the same and parallel therewith, is a piston rod 8 passing through the rear wall of the casing and fixed to a piston 9 slidable in a cylinder 10. The front end of the piston rod lies behind and engages with an ear 11 located on the wing 4 above the hinge axis. When air is admitted into the cylinder 10 behind the piston it forces the piston and rod forward, swinging the door open against the resistance of the spring-pressed plunger. In the opposite side of the casing is a gravity dog 12 adapted to drop behind a shoulder 13 located on the wing 3 above the hinge axis of the door; the parts being so proportioned that when the door is fully open the dog drops in place behind the shoulder and holds the door open until the dog is lifted out of the way.

Within the casing or housing is a contact

carrier the principal member of which is a flat box-like member 14 somewhat narrower than the casing. The member 14 is provided with upwardly-projecting ears 15 through 5 which pass stationary guide rods 16 extending lengthwise of the casing from the front to the rear walls of the latter. Each of the rods 16 passes through a stationary lug 17 extending downwardly from the top wall of 10 the casing. On each of the guide rods is a spring 18 bearing at one end against one of the lugs 17 and at its rear end against one of the ears or lugs 15 on the contact carrier. The springs 18 tend to hold the contact carrier 15 in its retracted idle position and, after the contact carrier has been projected forwardly so as to extend through the open doorway, the springs, when left free to do so, return the carrier to its idle position within 20 the casing. On one side of the member 14 is hung a gravity dog 19 having an upwardly-projecting nose 20 which is adapted to strike against a downwardly-projecting lug 21 on the dog 12, when the carrier is 25 projected forward and ride underneath this lug without tripping the dog. On the return movement of the contact carrier, the nose 20 strikes against the front side of the lug 21 but is prevented from swinging downwardly 30 past the lug by means of a pin or stop 22 lying behind the same and below the pivotal point. Consequently as the contact carrier is retracted the nose 20 acts on the lug 21, engaging with the inclined lower face 23 thereof, and forcing the locking dog for the door upwardly so as to release the door and permit the spring-pressed plunger to close the same.

The contact carrier is adapted to be projected through the open front of the casing by means of a piston rod 24 fixed to a piston 25 arranged in a cylinder 26 located just behind the rear wall of the casing near the top of the contact carrier and about midway between the sides of the casing. Instead of engaging directly with the member 14 of the contact carrier, the piston rod 24 is caused to engage with an arm 27 hinged at its lower end, as indicated at 28, to the contact carrier and rising vertically therefrom; said arm having a forwardly-projecting pin 29 which passes slidably through a lug 30 projecting upwardly from the top of the member 14. A strong spring 31 surrounds the member 29, bearing at its front end against the lug 30 and at its rear end against the upper end of the swinging arm 27. The contact carrier is brought to rest before the actuating piston 25 has fully completed its stroke, by bringing some portion of the carrier against a stationary stop; so that further compression of the spring 31 will occur after the carrier has been projected forward as far as it will go; and the carrier will therefore be yieldingly held in its extreme forward

position. A simple way to arrest the forward movement of the carrier is to permit the forward lugs or ears 15 to strike against the front wall of the housing or casing or preferably against bosses 32 projecting inwardly from said wall and capable of being machined so as to secure accurate adjustment of the carrier.

Above the member 27 is hinged a swinging dog 33 in position to drop down behind the upper end of the arm 27 at the completion of the working stroke of the actuating piston. In order to release the contact carrier so as to permit the springs 18 to return it to its retracted position, the member 33 must be 80 lifted out of engagement with the arm 27. In the arrangement shown, there is formed in the top of the casing a shallow vertical cylinder 34 containing a piston 35 having a rod or stem 36 which is loosely connected in 85 any suitable way to the free end of the member 33. Normally the weight of the parts and, if desired, a spring 37 acting on the member 33, permits the catch device to assume its locking position upon the projection forward of the carrier. When air under pressure is admitted into the cylinder 34 underneath the piston, the piston is forced up and unlocks the carrier. Air is supplied to the unlocking cylinder 34 through a passage 38 arranged in the top wall of the casing and extending to the front end of the casing where it is provided with a suitable terminal 39 adapted to make a tight joint with a corresponding terminal on another 100 coupler and thus establish communication between the passage 38 and the corresponding passage in another coupler.

The front end of the box-like member 14 of the contact carrier is filled with a body 40 of insulating material carrying the electrical contact pieces or terminals adapted to engage with similar parts in a coupler on another car. It is highly desirable that the contacts in two co-operating couplers slide upon each other when a coupling is effected, in order to keep the working faces of the contacts clean and insure a good electrical connection between each pair of co-operating contacts. Where the working faces of the contacts are approximately at right angles to the longitudinal axis of the coupler the sliding engagement between the contacts of two couplers can readily be brought about by means of a bodily lateral shifting of the couplers themselves. It may happen or be desirable so to support the electric couplers that they will be aligned before the contacts have come together or so soon thereafter that no substantial sliding of the contact faces on each other can take place. Under such conditions, it is highly desirable to provide means for insuring a sliding of the contacts upon each other. This may conveniently be accomplished by mounting some or 130

all of the contacts so that they are slideable in directions making an acute angle with the longitudinal axis of the coupler, so that as they slide in and out, their transverse working faces move bodily in the lateral direction.

In the arrangement shown there are twelve contact pieces arranged in two groups of six symmetrically disposed on opposite sides of a vertical plane containing the longitudinal axis of the coupler. The contacts 41, of one group, are shown as being stationary and as projecting only slightly from the front face of the body of insulating material 40. The contacts 42 of the other group are slideable in passages 43 parallel with each other and each making an acute angle with the longitudinal axis of the coupler. A spring 44 arranged within each passage behind the contact therein, holds the contact thrust forward a considerable distance beyond the front end of the insulating block. The contact faces 45 on the outer ends of the pieces 42 are arranged substantially at right angles to the longitudinal axis of the coupler. It will be seen that when two couplers are brought together, properly aligned, the contacts 41 in one coupler will engage with the contacts 42 of the other coupler, forcing those contacts backward against the resistance of the springs 44, and thus producing a bodily lateral shifting of the contact faces 45 and consequently a sliding engagement between these faces and the working faces of the contacts 41. It is desirable to reduce the number of electrical terminals in the coupler to a minimum and therefore, in order that each of the contact pieces 41 and 42 may at all times be a useful terminal, I have provided the coupler with a simple cross connecting switch which will serve properly to cross connect the wires of several similar cars each having only as many terminals in the coupler as there are circuits to be connected. In the bottom of the coupler casing are two transverse parallel bars 46 and 47 of insulating material on each of which are placed as many stationary contacts as there are terminals in the coupler, in the present instance twelve. The contacts on the bar 46 are indicated at 48 and on the bar 47 at 49. The elements 48 lie directly behind the corresponding elements in the row 49. At the rear end of the carrier 14 is a block of insulating material 50 underneath which extends a series of contact strips 51 equal in number to the contacts in each of the rows 48 and 49 and so disposed that each strip lies in a vertical plane containing one of the contacts in the row 48 and one of the contacts in the row 49. The terminal contacts 41 and 42 are connected to the strips 51 by means of suitable wires 52. The contact strips 51 lie somewhat above the stationary contacts 48 and 49 so as to leave room be-

tween the same for a co-operating switch member consisting of a long bar 55 of insulating material slideable on a pair of stationary guide rods 56 passing through the ends of the same and fixed at their ends in the front and rear walls of the casing. The member 55 is provided with two sets of contact fingers, a set 57 arranged on the upper side thereof and adapted to have sliding engagement with the strips 51, and a set 58 arranged on the under side and adapted to have sliding engagement with the stationary contacts 48 and 49. Corresponding contacts 57 and 58 are electrically connected together, this being conveniently accomplished by making one of the fingers 57 and the corresponding finger 58 out of a single piece of resilient metal suitably bent and attached to the supporting bar.

The parts are so proportioned that when they are in their idle positions as illustrated in Fig. 2, the fingers 58 lie behind the rear-most row 48 of the stationary contacts and therefore interrupt the electrical continuity between the terminals 41 and 42 and the wires or lines, (not shown,) which extend from the stationary contacts 48 and 49 in the form of a cable or otherwise through a suitable outlet 59 at the rear end of the casing. When the contact carrier is projected as heretofore explained, the movable member of the circuit closer may either be placed in a position in which it bridges the gaps between the contact strips 51 on the carrier and the stationary contacts 48 or in a position in which it bridges the gaps between the contact strips 51 and the stationary contacts 49. The same wires are of course connected to both the contacts 48 and the contacts 49, but in a reverse order in the row, thereby permitting the contacts 41 and 42 to be connected in either of two ways to the wires of which they are to form the terminals. The parts are so proportioned that the fingers 58 cannot at the same time be in engagement with both the contacts 48 and 49, but must leave the contacts of one row before they come into engagement with the contacts of the other row.

Two actuating devices are provided for the circuit-closing member 55 of the cross connecting switch, one of these actuators being intended to move the member 55 into operative relation to the row of contacts 48 and the other being designed to move the member 55 into operative relation to the row of contacts 49. In the arrangement shown, there are arranged in rear of the coupler casing two cylinders 60 and 61, these cylinders being placed in the vicinity of the longitudinal center of the coupler and with their axes in the same horizontal plane as the member 55. In the cylinder 60 is a piston 62 having a piston rod 63 which extends through the rear wall of the coupler

casing and engages with the rear edge of the member 55 without being attached to the latter. The piston 62 has a stroke sufficient to carry the member 55 from its idle position into a working position in operative relation to the contacts 48. In the cylinder 61 is a piston 64 having a rod 65 which extends through the rear wall of the coupler casing and is attached in any suitable manner to the member 55. The stroke of the piston 64 is sufficient to permit the piston to move the member 55 between its idle position and a working position in which the contact fingers 58 thereon engage with the stationary contacts 49. It will be seen that the piston 62 can be used only to move the member 55 in one direction while the other piston is effective in both directions. If desired, suitable spring catches 66 may be provided at the sides of the casing for co-operation with the ends of the member 55 when the latter is in its first working position, that is in operative relation to the contacts 48, so as to cause the member 55 to be yieldingly held in such working position and avoid the danger of accidental displacement after the operating air has been shut off. When the member 55 is moved into its second working position, that is in operative relation to the contacts 49, it is preferably positively locked in such position. In the arrangement shown, the piston rod 65 is provided with a notch 67 into which a spring-pressed plunger 68 is adapted to enter when the piston 64 has been moved into a position to bring the circuit-closing member 55 into operative relation to the contacts 49. The plunger 68 projects out from a suitable pneumatic cylinder 69 into which air may be admitted to retract the plunger and thus release the member 55 so that it can be drawn back into its idle position.

In addition to the air terminal 39 to which reference has heretofore been made, the coupler is provided with two other air terminals 70 and 71 joined together by a suitable passage 72 formed in the top wall of the casing. A branch passage 73 extends from the passage 72 into a valve chamber 74 the top of which may conveniently be formed by a detachable cover 75, as best shown in Figs. 1 and 4. This valve chamber lies at one side of the casing, directly above one of the wings of the door. In the valve chamber is a valve 76 having a stem 77 which projects down through the bottom of the chamber into the path of a shoulder 78 on the underlying door wing or flange; the parts being so proportioned that when the door approaches its fully open position, the shoulder 78 engages with the valve stem and forces the valve open, thus allowing air to flow from the top of the chamber 74 past the valve into the lower portion of the chamber from which it may then pass through a pipe

79 to the actuating cylinder 26 for the contact carrier. In other words, the contact carrier cannot be projected forwardly until after the door has been opened.

In the drawings I have shown a system of piping for insuring the proper operation of the various mechanisms on both of two connected cars when a valve on either car is manipulated.

Air may be received from any suitable source through a pipe 80. A master valve 81 is adapted to connect either of two pipes 82 and 83 to the pipe 80 or to atmosphere, the arrangement being preferably such that when either of the pipes 82 and 83 is connected to the pipe 80, the other will be connected to atmosphere. The pipe 82 leads directly to the rear end of the long cylinder 61. A branch pipe 84 extends from the pipe 82 to the passage 72 which connects together the two terminals 70 and 71 at the front of the coupler. Another branch pipe 85 extends from the pipe 84 into the rear end of the cylinder 60. The pipe 84 is also connected to the rear end of the door-opening cylinder 10, by means of a pipe 86, as best shown in Fig. 3. In the pipe 84, near the point where it is connected to the pipe 82, is a check valve 87 which prevents air from flowing from the pipe 84 into the pipe 82 but permits a flow in the opposite direction. In the pipe 85 is a pressure valve 88 which prevents a flow of air into the cylinder 60 until a predetermined pressure has been reached in the pipe 84. It will be seen that when the master valve is turned to admit air into the pipe 82, (assuming that two couplers have been brought into coupled relation to each other,) air will flow into the actuating cylinder 61 for the cross connecting switch, causing the member 55 to be pushed forward in the coupler until it is in operative relation to the contacts 49. At the same time air will flow into the door-opening cylinder 10 so that the door at the front end of the coupler will be opened. Air will also flow through the pipe 84 and passage 73 to the valve chamber 74 so that, as soon as the door of the coupler has been swung out of the way, air will be admitted to the actuating cylinder 26 for the contact carrier and the contact carrier will be forced outwardly through the open front end of the coupler. Air will flow through the terminals 70 and 71 to the corresponding terminals in the co-operating coupler so that air will flow in the other coupler through the passages 72 and 73 and also through the pipe 84; the flow of air through the pipe 84 being in the opposite direction from that in the coupler first considered, so that the air will be prevented by the check valve 87 from flowing into the cylinder 61 in the second coupler. Consequently while the door in the second coupler will be opened and the

contact carrier projected in precisely the same way as in the first coupler, air can enter only the short actuating cylinder for the cross connecting switch in the second coupler 5 and not the long cylinder, so that in the second coupler the member 55 of the cross connecting switch will be moved only into its first working position in which it lies in operative relation to the contacts 48. Consequently in one coupler the electric terminals 10 are connected to the circuits through the contacts 49 and in the other they are connected to the circuits through the contacts 48.

When it is desired to uncouple, the controlling valve on either car is moved into the position in which air is adapted to flow into the pipe 83 while the pipe 82 is connected to atmosphere. It will be seen that the air flows directly from the pipe 83 through 15 a pipe 90 into the front end of the cylinder 61 and, since the front ends of the cylinders 60 and 61 are connected together by a port 91, the air enters both the cylinders 60 and 61 and tends to force the pistons back. In 20 that car in which the movable member of the cross connecting switch has been moved only partially forward, the locking plunger associated with the long stroke piston will not have been brought into play and therefore 25 both of the pistons in that coupler will be forced back so as to bring the movable member 30 of the cross connecting switch into its idle position. In the coupler of the first car, that is the one in which the master valve was 35 operated to effect the coupling, the movable member of the cross connecting switch will be in its extreme forward position and therefore the piston rod associated with the long stroke piston will be positively locked 40 against retraction until the locking plunger is withdrawn. The withdrawal of the locking plunger 68 is effected by air which passes from the pipe 83 through a pipe 91 which is connected through a pressure valve 92 to 45 a pipe 93 leading to the pneumatic device 69 in which the locking plunger 68 is mounted. It is therefore necessary for pressure to build up in the pipes 90 and 91 before the long stroke actuating piston for the cross 50 connecting switch can be unlocked. The pipe 91 communicates with the passage 38 in the top wall of the coupler casing so that air flows directly from the pipe 83 through the pipe 91 into the releasing cylinder 34 for 55 the catch which locks the carrier in its projected position. Air flows from the passage 38 through the terminal 39 into the co-operating coupler.

It is desirable that the unlocking of the 60 car couplers be delayed until the electric couplers have been placed in idle condition. This may conveniently be accomplished by extending a branch pipe 94 from the pipe 93 to an unlocking cylinder 95 for a car coupler. With this arrangement, air cannot

flow into the unlocking cylinder until a predetermined pressure has been built up behind the pressure valve 92, which pressure may be great enough to insure that the catches for locking the contact carriers in 70 both couplers in their projected positions will be released before any air can flow to the unlocking devices for the air couplers.

In order to insure that the air will properly be exhausted in certain of the pipes 75 when air under pressure is admitted to other pipes, regardless of the position of the master valve, suitable "sniffle" valves or cocks 96 and 97 may be placed in the pipes 82 and 83, respectively; whereby these pipes are 80 open to atmosphere except when the pressure is above a predetermined minimum. Consequently whenever air is pushed back into either of these pipes by one of the pistons, it can escape through the "sniffle" 85 valve.

While I have illustrated and described with particularity only a single preferred form of my invention, I do not desire to be limited to the exact structural details 90 thus illustrated and described; but intend to cover all forms and arrangements which come within the terms employed in the definitions of my invention constituting the appended claims. 95

I claim:

1. In an electric coupler, a casing, a door for said casing, a movable contact carrier in the casing adapted to be projected when the door is open, an actuator for said carrier, 100 a controller for said actuator, and a part on the door in position to operate said controller as the door is opened.
2. In an electric coupler, a casing, a door for said casing, a movable contact carrier 105 in the casing adapted to be projected when the door is open, a pneumatic actuating device for said carrier, a controlling valve for said actuating device, and a part on said door in position to operate said valve when 110 the door is opened.
3. In an electric coupler, a casing, a door for said casing, a movable contact carrier in the casing adapted to be projected when the door is open, a pneumatic actuating device for said carrier, a normally-closed valve 115 controlling said actuator, and a part on said door in position to open said valve when the door is opened and hold the valve open while the door remains open. 120
4. In an electric coupler, a casing, a door for said casing, a movable contact carrier in the casing adapted to be projected when the door is open, a pneumatic actuating device for said carrier, a normally-closed valve 125 controlling said actuator, a part on said door in position to open said valve when the door is opened and hold the valve open while the door remains open, and a catch for holding said door open. 130

5. In an electric coupler, a casing, a door for said casing, a movable contact carrier in the casing adapted to be projected when the door is open, an actuator for said carrier, means associated with said door for controlling said actuator, a catch for holding said door open, and a part on said carrier for tripping the catch when the latter is retracted.
10. 6. In an electric coupler, a casing, a door for said casing, a movable contact carrier in the casing adapted to be projected when the door is open, an actuator for said carrier, means associated with said door for controlling said actuator, a catch for holding said door open, and a dog movably mounted on said carrier and constructed and arranged to travel past said catch without tripping it when the carrier is projected and to engage with the catch and trip it when the carrier is retracted.
15. 7. In an electric coupler, a casing, a door for said casing, a spring tending to close said door and hold it closed, means for opening the door against the tension of said spring, a catch for holding the door open, a contact carrier in the casing adapted to be projected when the door is open, a spring tending to move said carrier into and hold it in its retracted position, an actuator for projecting said carrier against the tension of its spring, means associated with the door for controlling said actuator, and means associated with the carrier for controlling said catch.
20. 8. In an electric coupler, a casing, a door for said casing, a spring tending to close said door and hold it closed, means for opening the door against the tension of said spring, a catch for holding the door open, a contact carrier in the casing adapted to be projected when the door is open, a spring tending to move said carrier into and hold it in its retracted position, an actuator for projecting said carrier against the tension of its spring, means associated with the door for controlling said actuator, means associated with the carrier for controlling said catch, and a catch for holding said carrier in its projected position.
25. 9. In an electric coupler, a casing, a door for said casing, a spring tending to close said door, a catch for holding the door open, means for opening the door, a contact carrier in the casing adapted to be projected when the door is open, an actuator for projecting said carrier, a controlling device for the actuator, means associated with said door for operating said controlling device when the door is moved into its open position, and means associated with said carrier for tripping said catch as the carrier moves from its projected position to its retracted position.
30. 10. In an electric coupler, a casing, a con-

tact carrier mounted in the casing so as to be movable between an idle position and a working position, a stop for arresting said carrier when it reaches its working position, a yieldable part on the carrier, an actuator 70 engaging with said yieldable part to move said carrier into its working position, and a spring arranged between said yieldable part and the main portion of the carrier so as to be stressed when the actuator is operated.

11. In an electric coupler, a casing, a contact carrier mounted in the casing so as to be movable between an idle position and a working position, a stop for arresting said carrier when it reaches its working position, a yieldable part on the carrier, an actuator 80 engaging with said yieldable part to move said carrier into its working position, a spring arranged between said yieldable part and the main portion of the carrier so as to be stressed when the actuator is operated, and a catch in position to engage with said yieldable part after said carrier has engaged said stop so as yieldingly to hold the carrier 90 against said stop.

12. In an electric coupler, a casing, a contact element mounted in the casing so as to be slidable in a direction forming an acute angle with the longitudinal axis of the casing, said element having at its front end a contact face arranged at right angles to said axis, a spring arranged between said element and said casing and tending constantly to hold said element in a forward position in which said contact face lies in front of said casing, and a second contact element having a contact face on its outer end, said second contact element being stationary and lying on the opposite side of said axis from the first contact element so as to be adapted to make a wiping engagement with a sliding contact element on a cooperating coupler.

13. In an electric coupler, a casing, two contact elements mounted in said casing and having on their outer ends contact faces arranged at right angles to the longitudinal axis of the casing, at least one of said elements lying at an acute angle to the longitudinal axis of the casing, a spring arranged 110 behind the latter contact element and between the same and the casing yieldingly to hold said element projecting a considerable distance beyond the front end of the casing, said elements being arranged symmetrically with respect to said axis so as to be capable of engaging with the contacts on a similar cooperating coupling.

14. In an electric coupler, a casing, two contact elements mounted in the casing and symmetrically disposed with respect to the longitudinal axis of the latter, one of said elements being stationary and projecting at its front end somewhat beyond the front end of the casing, the second contact element ex- 125 130

- tending at an acute angle to said axis and 5
slidable in the direction of its length, a
spring behind said second contact element
tending constantly to hold the same in a
forward position with its front end lying
in advance of the front end of the first
contact element, one of said contact elements
having at its front end a contact face at
right angles to said axis.
- 10 15. In an electric coupler, a casing, two
contact elements mounted in said casing and
having at their outer ends contact faces sym-
metrically disposed with respect to the lon-
gitudinal axis of the casing and lying at
right angles to said axis in planes disposed
from each other longitudinally of the cas-
ing and both lying in front of the casing,
the contact element whose contact face lies
farthest forward lying at an acute angle to
said longitudinal axis and being slidable in
the direction of its length, and a spring ar-
ranged between the latter contact element
and the casing for yieldingly holding the
contact element in its advanced position and
25 permitting it to slide back against the re-
sistance of the spring.
16. In an electric coupler, a casing, two
groups of contact elements disposed on op-
posite sides of a vertical plane containing
30 the longitudinal axis of the coupler, said
contact elements projecting at their front
ends beyond the casing and terminating in
transverse contact faces adapted to make
butt contact with the contact elements of the
35 cooperating coupler, the elements in one of
the groups lying at an acute angle to said
plane and to the contacts of the other group
and being movable with respect to the casing
in the direction of their lengths, and springs
40 between the elements of the latter group and
the casing tending constantly to hold said
elements with their forward ends advanced
beyond the forward ends of the elements of
the other group.
- 45 17. In an electric coupler, a member of
insulating material having on one side of
the longitudinal axis a group of parallel
passages forming an acute angle with said
axis, contact elements slidable in said pas-
50 sages, springs behind said elements tending
to hold them thrust forward with their front
ends projecting beyond said member, and
a group of stationary contact elements equal
in number to the pieces in the aforesaid
55 passages disposed on the opposite side of
said axis, all of said contact elements hav-
ing on their front ends contact faces ar-
ranged approximately at right angles to
said axis.
- 60 18. In an electric coupler, a contact car-
rier movable between an idle position and a
working position, two similar parallel rows
of stationary contacts having faces lying in
a plane parallel to the path of movement of
65 the carrier, a row of contact pieces equal in
number and similar in spacing to the con-
tacts in each of the aforesaid rows mounted
on the carrier so as to face and parallel the
said rows of contacts, and a circuit closer
having two working positions in one of 70
which it is adapted to connect each of said
contact pieces with the corresponding con-
tact in one of the said rows while in the
other position it is adapted to connect each
of said contact pieces with the correspond- 75
ing contact in the other of said rows.
19. In an electric coupler, a casing, a con-
tact carrier arranged within the casing and
having contact elements adapted to engage
with similar elements in another coupler, 80
said carrier being movable between an idle
position and a working position, auxiliary
contacts on the carrier and an electrical con-
nection with said contact elements, two sets
of stationary contacts arranged within the 85
casing adjacent to said carrier, and a circuit
closer in the casing movable independently
of said carrier and constructed and ar-
ranged electrically to connect said auxiliary
contacts to either of said sets of stationary 90
contacts when the carrier is in its working
position.
20. In an electric coupler, a casing, a
contact carrier in said casing having contact
elements adapted to engage with similar ele- 95
ments in another coupler, auxiliary contacts
on said carrier electrically connected to said
contact elements, said carrier being movable
between an idle position and a working po-
sition, two sets of stationary contacts in said 100
casing, and a circuit closer movable in said
casing independently of said carrier be-
tween an idle position and two working po-
sitions; said circuit closer being constructed
and arranged electrically to disconnect said 105
auxiliary contacts from said stationary con-
tacts when both the carrier and the circuit
closer are in their idle positions; electrically
to connect said auxiliary contacts with one
set of said stationary contacts when the car- 110
rier is in its working position and said cir-
cuit closer is in one of its working positions;
and electrically to connect said auxiliary
contacts with the other set of stationary con-
tacts when said circuit closer is in its other 115
working position.
21. In an electric coupler, a casing, a mov-
able contact carrier in said casing having
contact elements adapted to engage with
similar elements on another coupler, auxil- 120
iary contacts on said carrier electrically
connected to said contact elements, two sets
of stationary contacts in said casing, and a
circuit closer movable in said casing between
an idle position and two working positions, 125
said circuit closer being constructed and ar-
ranged electrically to connect said auxiliary
contacts to one set of said stationary con-
tacts in one working position and electri-
cally to connect said auxiliary contacts to 130

- the other set of stationary contacts in the other working position.
22. In an electric coupler, a casing, a movable contact carrier in the casing having contact elements adapted to engage with similar elements on another coupler, auxiliary contacts on the carrier electrically connected to said contact elements, two sets of stationary contacts in the casing, a circuit closer movable in the casing between an idle position and two working positions, said circuit closer being constructed and arranged electrically to connect said auxiliary contacts to one of said sets of stationary contacts in one working position and electrically to connect auxiliary contacts to the other set of stationary contacts in the other working position, and means for locking said circuit closer in one of its positions.
23. In an electric coupler, a circuit-controlling element having an idle position and two working positions, two pneumatic actuating means for moving said element into said working positions, piping leading to said actuators and to an air terminal adapted to register with a corresponding terminal on another coupler, and a check valve so positioned in said piping that air flowing toward said terminal in said piping will pass to both actuators while air flowing through said terminal from another coupler will pass to only one of said actuators.
24. In an electric coupler, a circuit-controlling element, a pneumatic actuator for said element, a catch for holding said element in a predetermined position, a pneumatic releasing device for the catch, connected piping leading to said actuator, and said releasing device; and a pressure valve in said piping in position to require air pressure to build up after air is admitted to said actuator before it can enter said releasing device.
25. In combination, an electric coupler having a circuit-controlling element, a pneumatic actuator for said element, a catch for holding said element in a predetermined position, a pneumatic unlocking device for a car coupler, piping directly connecting said actuating device, said releasing device and said unlocking device; a master controlling valve for admitting air to said piping, and a pressure valve in said piping between said actuator and the said two devices.
26. In an electric coupler, a casing having a door, a pneumatic actuator for opening said door, a contact carrier in said casing, a pneumatic actuator for said carrier, a circuit closer in the casing co-operating with said carrier, a pneumatic actuator for said circuit closer, piping connecting said actuators together, a valve for admitting air to said piping, and a door-controlled valve in said piping at a point to control the admission of air to the actuator for the contact carrier.
27. In an electric coupler, a casing, a contact carrier in the casing, an actuator for said carrier, a circuit closer in the casing having two working positions and an idle position and co-operating with the carrier to produce different circuit connections in said two working positions, two actuating devices for said circuit closer one having a long stroke and the other a short stroke, piping connecting said actuator and said actuating devices together and to an air terminal at the front end of said casing, and a check valve in said piping so positioned that when air flows in one direction in said piping it will enter said actuator and both of said actuating devices and when it flows in the other direction will enter said actuator and only one of said actuating devices.
28. In an electric coupler, a series of contact elements adapted to engage with similar contact elements on another coupler, a cross connecting switch including two sets of stationary contacts and a movable circuit closer, a pneumatic actuating device for moving said circuit closer into engagement with one of said sets of stationary contacts, a second pneumatic actuating device for moving said circuit closer into engagement with the other set of stationary contacts, and piping associated with said actuating devices constructed and arranged to cause one of said actuating devices to come into play when the air is delivered from the car on which the coupler is mounted and to cause the other actuating device to come into play when the air comes from the car on which a co-operating coupler is mounted.
29. In an electric coupler, contact elements adapted to engage with similar contact elements on a co-operating coupler, a cross connecting switch having two circuit closing positions and a movable member movable independently of said contact elements, two pneumatic actuating devices for said movable switch member, one of said actuating devices being adapted to move said member into one of its circuit closing positions, the other actuating device being adapted to move said member in its other circuit closing position; and a piping system connected and arranged to bring one of said actuating devices into play when air is supplied from the car on which the coupler is mounted and to cause the other actuating device to come into play when the air is supplied from a car on which a co-operating coupler is mounted.
30. In an electric coupler, contact elements adapted to engage with similar contact elements on a co-operating coupler, a cross connecting switch having two circuit closing positions and a movable member movable independently of said contact elements, two pneumatic actuating devices for said movable switch member, one of said actuating devices being adapted to move said

- member into one of its circuit closing positions, the other actuating device being adapted to move said member in its other circuit closing position; and a piping system connected and arranged to bring one of said actuating devices into play when air is supplied from the car on which the coupler is mounted and to cause the other actuating device to come into play when the air is supplied from a car on which a co-operating coupler is mounted, and to cause both of said actuating devices to be retracted to bring said movable switch member into an idle position when air is supplied from either either of said two cars in uncoupling.
31. In an electric coupler, a casing, two contact elements projecting beyond said casing and symmetrically disposed with respect to the longitudinal axis of the casing, said contact elements having faces arranged at right angles to said axis, one of said ele-
- ments being stationary, the other of said elements being slidably mounted at an acute angle to said axis, and a spring tending constantly to hold the latter contact element in a forward position.
32. In an electric coupler, a casing, two contact elements projecting beyond said casing and symmetrically disposed with respect to the longitudinal axis of the latter, said contact elements having faces arranged at right angles to said axis, one of said elements being so mounted that the distance between its contact face and said axis remains constant, the other of said elements being slidably mounted at an acute angle to said axis, and a spring tending constantly to hold the latter contact element in its forward position.
- In testimony whereof, I sign this specification.

HERBERT E. VAN DORN.
